(21) Appl. No.: **29/344,930**

Chef's Catalog, p. 72, OXO measuring cup.

(22) Filed: **Oct. 6, 2009**

Primary Examiner—Terry A Wallace

(74) Attorney, Agent, or Firm—McDermott Will & Emery LLP

Related U.S. Application Data

CLAIM

(63) Continuation of application No. 29/334,175, filed on Mar. 21, 2009, now abandoned.

We claim the ornamental design for a measuring container, as shown and described.

(51) **LOC (9) Cl.** **10-04**

DESCRIPTION

(52) **U.S. Cl.** **D10/46.2**

FIG. 1 is a perspective view of a measuring container according to the new design;

(58) **Field of Classification Search** D7/509,

FIG. 2 is a front view of a measuring container according to the new design shown in FIG. 1;

D7/523, 316; D10/46.2, 46.3; 73/426-429;

FIG. 3 is a left side elevation view of a measuring container according to the new design shown in FIG. 1;

206/514; 222/158

FIG. 4 is a right side elevation view of a measuring container according to the new design shown in FIG. 1;

See application file for complete search history.

FIG. 5 is a top view of the measuring container shown in FIG. 1;

(56) **References Cited**

FIG. 6 is a bottom view of the measuring container shown in FIG. 1; and,

U.S. PATENT DOCUMENTS

FIG. 7 is a rear view of the measuring container shown in FIG. 1.
